UNITED STATES PATENT OFFICE.

THOMAS TIPPING, OF ASHTON-UPON-RIBBLE, AND EDWARD FLETCHER, OF PRESTON, ENGLAND, ASSIGNORS TO WILLIAM LEWIS HOLLAND, OF PRESTON, ENGLAND.

APPARATUS FOR THE STOPPAGE OF WATER FROM AUTOMATIC SPRINKLER-HEADS AFTER FIRES OR ACCIDENTS.

SPECIFICATION forming part of Letters Patent No. 700,103, dated May 13, 1902.

Application filed February 13, 1902. Serial No. 93,989. (No model.)

To all whom it may concern:

Be it known that we, THOMAS TIPPING, of 51 Tulketh Crescent, Ashton-upon-Ribble, and EDWARD FLETCHER, of Maynard street, 5 Preston, in the county of Lancaster, England, have invented an Apparatus for the Stoppage of Water from Automatic Sprinkler-Heads After Fire or Accident, of which the following is a specification.

10 This invention consists of an apparatus designed to instantly stop the escape of water from automatic sprinkler-heads after the same have been discharged by fire or accidentally.

15 In the accompanying two sheets of drawings, Figures 1 and 2 are elevations of the apparatus made with two heads each adapted to close a different type of automatic sprinkler. Figs. 3 and 4, Figs. 5 and 6, and Figs. 20 7 and 8 are elevations of three different forms of the apparatus, each made with a single head and adapted to close different types of automatic sprinklers.

Similar letters refer to similar parts throughout the several views.

In Figs. 1 and 2, *a* designates the water-supply pipe of an automatic sprinkler installation, and in order to illustrate the application of the double-headed apparatus to two 30 different types of sprinklers the drawing shows on the left-hand side a "Titan" or similar form of sealed sprinkler *b*, while on the right-hand side is a "Grinnell" or similar form of valve-sprinkler *b'*. The apparatus 35 consists of a pole *c*, upon the upper end of which is secured a frame *d*, and on the left-hand side this frame has a horizontal fork *e*, adapted to fit over the body of the sprinkler *b*. The frame *d* has also two horizontal arms 40 or projections *d'* *d''*, one above the other, and a rod *f*, with a valve-shaped top *f'*, is fitted to slide vertically in holes in these arms. A lever *g* is pivoted to the frame *d*, and one end of this lever lies in a slot in the rod *f* and 45 the other end is connected by a wire *h* to a hand-lever *i*, (see Figs. 7 and 8,) which is pivoted to the pole *c* and has ratchet-teeth formed upon its segmental end, and by means of a pawl or catch *j* the hand-lever *i* can be locked

in either of the positions shown. On the 50 right-hand side of the frame *d*, Figs. 1 and 2, is formed a horizontally-projecting wedge-shaped head *k*, adapted to be inserted between the bridge or gallery and the valve-seating on the under side of the body of the 55 Grinnell or similar sprinkler *b'*. A lever *l* is pivoted to the frame *d*, and one end of this lever has a valve *l'* and the other end is connected below by the wire *h* to a second lever *i* with ratchet-teeth and a retaining-pawl *j*, 60 as already described. In operation when it is desired to stop the rush of water from a sprinkler the operator, standing on the floor, raises the pole *c* and places the finger-like projections of the fork *e* in some makes of 65 sprinklers over the body of the sprinkler *b*, one finger on each side of it, while in other makes of sprinkler the wedge-shaped head *k* is inserted between the bridge or gallery and the body of the sprinkler *b'*; and by depressing the hand-levers *i* the levers *g* and *l* are 70 actuated and close their respective sprinklers—in one case, *b*, by means of the vertically-sliding rod *f* and in the other case by means of the lever *l*.

75 Figs. 3 and 4 illustrate the apparatus as adapted for sealing a discharged sprinkler *b''* of the "Witter" or similar type. In these views the fork *e*, instead of being fixed, is carried by a vertical bar *m*, supported and 80 guided in projecting arms *d''* *d'''* on the frame *d*. A valve or stopper *n'* is carried by an arm *n*, fixed on or formed with the frame *d*, and the fork *e* is held normally raised by a coiled spring *o*. When, however, it is desired to 85 stop the discharged sprinkler *b''* the fork *e* is placed over the body thereof, the valve *n'* is pressed up into the sprinkler, and the parts are drawn closely together and the sprinkler sealed by operating the wire *h* and then locking the hand-lever *i*, with which it is connected, (see Figs. 7 and 8,) in the manner previously described.

90 Figs. 5 and 6 illustrate the right-hand side of the apparatus shown in Figs. 1 and 2, but 95 in this case made with a single head and mounted alone on a pole *c*, and in like manner Figs. 7 and 8 show a modified form of the

apparatus, Figs. 3 and 4, adapted to seal a sprinkler *b* of the type shown on the left-hand side of Figs. 1 and 2. In this arrangement the valve or stopper *n'* will either push up the sprinkler-valve or will directly seat upon the discharge-opening and itself seal the sprinkler in those cases in which the valve falls away when the sprinkler is discharged.

10 It will be readily understood that the apparatus may be slightly varied or modified to suit corresponding variations or modifications in the construction of the automatic sprinkler, and, further, that the apparatus will act equally well if applied to sprinklers which are arranged to discharge upward instead of downward, as shown. In some cases—as, for example, when sprinklers are placed near the roof and are arranged to discharge upward—the apparatus would be mounted upon a short handle to enable the sprinkler to be readily closed from above it, and in such cases the ratchet hand-lever *i* and retaining-pawl *j* might be dispensed with and

the movable part held by a screw and nut or equivalent device.

What we claim as our invention, and desire to secure by Letters Patent of the United States, is—

The combination with an automatic sprinkler installation, of an apparatus for sealing a discharged sprinkler, said apparatus consisting, in its essential features, of a frame mounted upon a pole, a part carried by the frame and arranged to engage the body of the sprinkler, a valvular part arranged to seal the sprinkler and operating means, such as a connected ratchet hand-lever and retaining-pawl, substantially as and for the purposes herein set forth.

In witness whereof we have hereunto set our hands in presence of two witnesses.

THOMAS TIPPING.
EDWARD FLETCHER.
